INVENTOR.
FRANK M. STOLL

BY

O. J. Gallenbach
ATTORNEY.

UNITED STATES PATENT OFFICE.

FRANK M. STOLL, OF DENVER, COLORADO, ASSIGNOR TO STOLL MANUFACTURING COMPANY, OF DENVER, COLORADO.

TENT.

Application filed June 18, 1925. Serial No. 37,965.

This invention relates to means for supporting a rectangular tent of the type known as a "palmetto tent" and has for its principal object the provision of a supporting structure which eliminates poles in the floor space of the tent and which removes the necessity for guy ropes.

Another object of the invention is to provide a substantial truss structure, for the support of the top and sides of the tent, which will have but few separate parts and which can be folded into a compact bundle.

Still another object is to provide means, operable from within the tent, for tightening or loosening the sides and top of the tent.

A further object is to so arrange the supports and their connections that the tent may easily and quickly be erected or collapsed.

Other objects and advantages reside in the detail construction of the tent and its supporting structure, which is designed for simplicity, economy, and efficiency. These will become apparent from the following description.

In the following detailed description of the invention reference is had to the accompanying drawing which forms a part hereof. Like numerals refer to like parts in all views of the drawing and throughout the description.

In the drawing:

Fig. 1 is a perspective view of my improved tent supporting structure. In this view the tent covering is shown in outline only, in broken line.

Figs. 2 and 3 are detail perspective views on the inside of the tent, illustrating details of the supporting structure.

Fig. 4 is a detail view illustrating the method of folding the top truss.

Fig. 5 is a similar view illustrating the method of folding the side supports.

Fig. 6 illustrates the method of connecting the truss brace to the side supports.

Fig. 7 illustrates the means employed for tightening or loosening the tent covering.

Fig. 8 illustrates the method of connecting the hip poles of the tent.

Fig. 9 illustrates the locking means, for locking the side poles in the extended position.

The tent covering, such as canvas, duck or similar material, is illustrated at 10, and is formed with a rectangular bottom, from

which, rise inward-depending sides, connecting, at the hip of the tent, with a pyramidal top.

The invention comprises a supporting structure for the top 10, which comprises two side poles, each having an upper and lower section 11 and 12 respectively, hinged together at 13, and each supporting a truss structure, for the support of the tent sides, and a second truss structure for the support of the tent top.

The truss structure for the support of the top comprises two rafter poles 14, hinged together at the peak of the tent, as shown at 15. To each free extremity of the rafter poles 14 a stub 16 is hinged, as illustrated at 17, which is braced from the rafter pole by an angle brace 18. The brace 18 is hinged to the rafter pole at 19, its other extremity being arranged to detachably engage a pin 20 in the stub 16.

The method of engaging the pin 20 is illustrated in detail in Fig. 6. A slot 21 is cut in brace 18 adapted to be passed upward around the pin 20. A slider 22 is carried on the brace 18, provided with a projecting tongue 23. The tongue 23 closes the slot 21, after the pin 20 is in place therein, and securely locks the angle brace 18 to the stub 16. The stubs 16 are arranged to be passed into the upper extremities of the upper sections 11 of the side poles when the tent is erected.

The top truss is folded by disengaging the angle braces 18 from the stubs 16 and folding the former as indicated by the arrows 18', and the latter as indicated by the arrows 16'. Both the rafter poles 14 and the stubs 16 are channel-shaped in cross section so that both the stubs 16 and the braces 18 will lie within the rafter poles 14 when folded. The two rafter poles are then folded together, as indicated by the arrows 14', to the broken line position of Fig. 4.

The truss structure for supporting the tent sides comprises sleeves 24, arranged to slide on each of the upper sections 11 of the side poles, from each of which project two hinged truss rods 25, to the extremity of each of which a section of hip pole 26 is hinged at 27. The co-acting sections of the hip pole 26 are joined by means of the connection, illustrated in detail in Fig. 8.

This connection comprises a notched extremity 28 formed on one of the sections 26

and a hooked extremity 29 formed on the other. The notched extremity carries a stationary pin 30 and the hooked extremity carries a movable spring-actuated pin 31. 5 When attaching the sections, the hooked extremity 29 is placed over the pin 30 and the two sections 26 are forced into alignment. This brings the movable pin into the notch 28 where it is held by the action of spring 10 32 until withdrawn by a thumb catch 33.

As the two sections 26 of the hip poles are forced into alignment they will act to stretch two of the tent sides and top horizontally. The remaining two sides of the 15 tent and top are stretched by forcing the sleeve 24 upward on the side poles. This extends the reach of the truss rods 25 and forces the hip poles 26 outward.

The sleeves 24 are locked in any desired 20 position on the side poles by means of dogs 34 carried by the sleeves, and which are arranged to engage the teeth of rack bars 35 carried by the sections 11 of the side poles.

The two sections 11 and 12 are locked in 25 alignment at their hinge 13 as indicated in Fig. 9, by means of a movable pin 36, carried by the section 11, and which is arranged to be forced into a notch in the extremity of the section 12, by a spring 37 when the 30 sections are brought into alignment. A thumb catch 38 is provided for withdrawing the pin 36 from the notch. As the two sections 11 and 12 are brought into alignment the entire tent covering will be 35 stretched vertically.

The side poles and their attached truss structures are folded as indicated in Fig. 5, after the two sections of the two hip poles have been disconnected at the joint of Fig. 40 8, the sections 26 are folded, as indicated by the arrow 26', upon the truss rods 25, which they will enclose. The truss rods 25, with the folded over sections 26, are then folded, as indicated by the arrows 25', against the 45 section 11 of the side pole. The hinge, of Fig. 9, is then released and the section 12 is folded, as indicated by the arrow 12', over the section 11, which it will enclose. The folded top truss and side poles may then be 50 rolled in the tent covering.

It is desired to call attention to the fact, that, there are only three separate pieces to the entire supporting structure; the two side poles with their attached truss rods 55 and hip pole sections, and the top truss.

Attached to the tent covering 10, at each corner, at the hip line, is an angle shield 39, shown in detail in Fig. 2, and adapted to receive the hinge points 27 of the hip rod 60 sections 26 and the truss rods 25.

Chains 40 are attached to the shields 39 and extend across the sides of the tent, having the side poles, at the hip line thereof. The chains 40 are preferably contained in 65 sockets 41 formed on the covering 10. The

chains 40 act as a tie between the extremities of the truss rods 25 thus completing the truss and relieving the covering 10 from the strain thereof. At the mid point of the chains 40, a socket 42 is secured, into 70 which, the hinge point 17 fits. This socket 42 serves to align the side poles at the middle of the tent sides. The shields 39, chains 40 and sockets 42 are secured to, and carried as an integral part of the covering. 75

The supporting structure is prevented from falling by stakes 43 which are driven into the ground and secured to the covering 10 at each corner thereof.

A socket 44 is suspended from the hinge 80 15 and arranged to fold within the rafter poles. An erecting pole (not shown) may be placed in the socket 44 to support the top truss while the side poles are being put in place. 85

While a specific form of the improvement has been described and illustrated herein, it is desired to be understood that the same may be varied, within the scope of the appended claims, without departing from the 90 spirit of the invention.

Having thus described the invention, what I claim and desire secured by Letters Patent is:—

1. Means for supporting the covering of 95 a tent having four sides and a top, comprising poles adapted to extend upward substantially on a medial line on two opposite sides of said tent; arms extending oppositely outward from each of said side poles to the four corners of said tent; poles connecting the extremities of said arms and adapted to support the remaining two sides and upwardly projecting truss arms carried by said side poles and adapted to support the top of 100 said tent and means for tying the extremities of each pair of oppositely extending arms together. 105

2. Means for supporting the covering of 110 a tent having four sides and a top, comprising poles adapted to extend upward substantially on a medial line on each of two opposite sides of said tent; arms extending oppositely outward from each of said side poles to the four corners of said tent; poles connecting the extremities of said arms and adapted to support the remaining two sides and upwardly projecting truss arms carried by 115 said side poles and adapted to support the top of said tent and means for tying the extremities of each pair of oppositely extending arms together said means comprising a flexible member carried by said covering. 120

3. Means for supporting the covering of 125 a tent, having four sides and a top, comprising foldable side poles adapted to extend upward substantially along the medial line of each of two opposite sides; detachable arms carried by said side poles and adapt- 130

ed to project at an upward angle therefrom to support said top; oppositely extending truss rods carried by said side poles and adapted to support the corners of said tent; 5 hip poles hinged to each said truss rods and adapted to support the remaining two sides of said tent and means for securing the co-acting extremities of said hip poles together.

4. In a tent supporting structure having 10 co-acting poles, means for connecting the extremities of said co-acting poles, comprising a hook shaped end on the first extremity adapted to engage a pin on the second extremity and a groove in the end of the second extremity adapted to engage a spring actuated latch on the first extremity.

5. In a tent supporting structure having hinged poles, means for locking said hinged poles in the extended position, comprising 20 a pivot pin securing said poles together; an extension on one of said poles adapted to limit the movement about said pivot pin in one direction and a movable latch adapted to engage a notch in the other of said poles 25 to limit movement in the other direction.

6. Means for supporting the covering of a tent comprising poles adapted to extend upward substantially on a medial line at two opposite sides of said tent; a flexible 30 truss connected to the upper extremities of said poles and extending across the top of said tent; arms projecting oppositely out-

ward from each of said poles to the four corners of said tent, the position of said arms on said poles being variable. 35

7. In a rectangular tent having poles adjacent opposite walls thereof; truss rods extending from said poles at an upward angle to the corners of said tent; and flexible means extending between the extremities of 40 said truss rods and across said poles to support said extremities.

8. The combination in a rectangular tent having poles adjacent opposite walls thereof; truss rods extending from said poles at 45 an upward angle to the corners of said tent; flexible means extending between the extremities of said truss rods and across said poles to support said extremities; and maintaining means carried by said flexible means 50 and adapted to maintain said poles intermediate said extremities.

9. In a rectangular tent having poles adjacent the opposite walls thereof; truss rods extending from said poles at an upward 55 angle to the corners of said tent; sockets carried by said tent at its corners to receive the extremities of said poles; and flexible means extending between the sockets across said opposite walls to prevent separation of 60 said sockets by said truss rods.

In testimony whereof, I affix my signature.

FRANK M. STOLL.
